UNITED STATES PATENT OFFICE.

JAMES H. REICHART, OF MUNCIE, INDIANA.

DESIGN FOR A CASING FOR CORN-POPPING MACHINE.

Application filed June 18, 1928. Serial No. 27,189. Term of patent 14 years.

To all whom it may concern:

Be it known that I, JAMES H. REICHART, a citizen of the United States, residing at Muncie, in the county of Delaware and State of Indiana, have invented a new, original, and ornamental Design for Casing for Corn-Popping Machine, of which the following is a specification, reference being had to the accompanying drawing, forming part thereof.

In the drawings, Fig. 1 is an elevation of a casing for corn popping machine, showing my new design. Fig. 2 is a top plan view thereof.

I claim:

The ornamental design for a casing for corn popping machine, as shown.

JAMES H. REICHART.
